UNITED STATES PATENT OFFICE.

MINNIE S. HULLEY, OF WOODHAVEN, NEW YORK.

PROTECTIVE APRON.

Application filed August 24, 1921. Serial No. 495,040.

To all whom it may concern:

Be it known that I, MINNIE S. HULLEY, citizen of the United States, residing at Woodhaven, in the county of Queens and State of New York, have invented certain new and useful Improvements in Protective Aprons, of which the following is a specification.

This invention relates to improvements 10 in undergarments and more particularly to an improvement in protective aprons for wear by women, the primary object of the invention being to provide an apron which will afford ample protection to the clothing 15 and yet will not present any of the disadvantages attending the use of the usual forms of protective aprons.

One form of protective apron commonly worn is made of rubberized cloth but presents the disadvantage that the material is liable to crack, thus permitting the permeation of perspiration to the clothing, the material is relatively stiff and uncomfortable to wear, and is, furthermore, of such a 25 nature as to tend to increase the secretion of perspiration. The present invention, therefore, contemplates the provision of a protective apron for the purpose stated, made from some light cloth material such, 30 for example, as crêpe or crêpe de chine and having an insert or gore, at its central portion, of thin rubber, with the result that the article as a whole is light in weight, will conform closely to the contour of the 35 part of the body to which it is applied without creating noticeable heat, and will be entirely comfortable to the wearer and serve in a highly effectual manner to protect the clothing.

Another object of the invention is to provide a protective garment of the class described which may be worn either with or without other under garments and which may be readily applied and removed as occasion requires.

In the accompanying drawing:

Figure 1 is a perspective view illustrating the manner of wearing the protective garment embodying the invention,

Figure 2 is a plan view of the garment spread out.

The garment, generally speaking, comprises an apron which is indicated in general by the numeral 1. The waist portion of the garment is indicated by the numeral 2 and from this portion the apron 1 is gradually

widened in a downward direction as best shown in Figure 2 of the drawing, and is provided at its lower part with relatively diverging leg portions indicated by the 60 numeral 3. The apron comprises two side sections indicated by the numeral 4 which throughout their upper portions are united at their meeting edges by a seam 5. These side portions 4 may be made of any suitable 65 thin cloth material such for example as crêpe or crêpe de chine and may be given a desired degree of fullness to insure of proper fitting of the garment to the body when applied. Below the seam 5 and between the 70 same and the lower end of the garment, the side portions 4 have their adjacent edges cut away along curved lines extending in a general outward direction as indicated by the numeral 6, the cut away edge portions 6 75 meeting at the lower end of the seam 5 but being relatively spaced at the lower end of the garment as shown in Figure 2.

The space between the edges 6 of the side portions 4 is spanned by a gore 7 which is 80 united at its lateral edges to the edges 6 of the said side portions 4 and which may or may not be provided with a medial seam 8, as found desirable. If it is provided with such a seam, this seam will extend in alignment with and constitute a continuation of the seam 5. The gore 7 is preferably made of a good quality of thin rubber, and because of the outwardly curved lines of extent of the edges 6 of the side portions 4, the gore 90 7 is gradually increased in width from its upper end to a point near its lower end, from which point it is gradually decreased in width. Thus, the gore is of a marginal 95 contour to best afford protection to the clothing by completely covering the part of the body which it is desired to protect from contact by the clothing.

The leg portions 3 are located at opposite sides of the lower end portion of the gore 100 7 as clearly shown in Figure 2, and, as previously stated, diverge with relation to each other. These leg portions may be of any desired length and, when the article is properly applied to the person as illustrated 105 in Figure 1 of the drawing, are designed to partly encompass the rear sides of the thighs.

In order that the garment may be attached and held in place, it is provided at 110 its waist portion 2, with a waist belt indicated by the numeral 9. This belt may be

of elastic or any other suitable material and extends along the upper end edge of the apron 1 and projects freely beyond the upper corners of the apron as indicated by 5 the numeral 10, the projecting parts 10 being designed to be brought about the front of the body and secured together temporarily by snap fastenings 11 provided at their extremities.

10 In order that the leg portions 3 of the apron may be held to the limbs of the wearer, leg straps 12 are secured along the lower edges of the leg portions 3 and have portions 13 projecting beyond the corners 15 of the said leg portions, and these projecting portions as well as the attached portions of the straps are designed to be brought about the limbs and secured temporarily by snap fastening elements 14 located at the extremities of the said straps 12.

It will be evident by reference to Figure 1 of the drawing, that the article is to be applied in such position that it will cover the seat of the wearer, the gore 7 being in 25 this manner positioned to most effectually protect the outer clothing being worn.

Having thus described the invention, what is claimed as new is:

1. An article of the class described comprising an apron having a relatively narrow upper end, the apron being continuously

increased in width in the direction of its lower end, means at the upper end of the apron for attaching said end, the lower end of the apron being medially recessed to provide oppositely diverging leg portions, means at the lower end of each leg portion extending diagonally with relation to the vertical median line of the apron for attaching the leg portion to the limb, and a gore of thin sheet rubber set into the lower portion of the apron and extending from a point adjacent the upper end of the apron to the inner edges of the said leg portions. 35 40

2. An article of the class described comprising an apron consisting of two symmetrical sections united along the upper portion of their meeting edges by a seam and having the lower portions of their said edges cut away along oppositely curving lines, a gore of thin sheet rubber set into the opening provided between the said cut away edge portions of the said apron sections and united at its margins to the said edges, the lower edge of the apron being recessed to provide diverging leg portions, attaching means at the upper end of the apron, and an attaching means at the lower end of each leg portion. 45 50 55

In testimony whereof I affix my signature. 60

MINNIE S. HULLEY. [L. S.]
